Primary Examiner — Marianne N Pandozzi(74) *Attorney, Agent, or Firm* — Charles A. Lemaire;
Jonathan M. Rixen; Lemaire Patent Law Firm, P.L.L.C.(57) **CLAIM**

The ornamental design for a straw holder with strap, as shown and described.

DESCRIPTION

FIG. 1 is a perspective view of the decorative straw holder with strap showing the new design;

FIG. 2 is a top view thereof;

FIG. 3 is a bottom view thereof;

FIG. 4 is a right-side view thereof;

FIG. 5 is a left-side view thereof;

FIG. 6 is a front view thereof; and,

FIG. 7 is a back view thereof.

The broken lines in FIGS. 1-7 are for the purpose of illustrating portions of the straw holder with strap that are not part of the claimed design.

1 Claim, 2 Drawing Sheets(56)
